UNITED STATES PATENT OFFICE.

WILLIAM H. HANNAFORD, OF LAKE, ILLINOIS.

BOOT AND SHOE.

SPECIFICATION forming part of Letters Patent No. 230,273, dated July 20, 1880.

Application filed February 3, 1880.

To all whom it may concern:

Be it known that I, WILLIAM H. HANNAFORD, of the town of Lake, in the county of Cook and State of Illinois, have invented certain new and useful Improvements in Boots and Shoes, of which the following is a specification.

My invention relates to an improvement upon the device patented by me October 14, 1879, (Patent No. 220,475;) and its object is to provide the boot or shoe with a double elastic air-chamber between its soles, which will give greater elasticity and secure a more complete ventilation, and with a better and more secure manner of fastening the intermediate elastic lift of the heel to the sole and to the wearing-lifts.

The invention consists, first, in the combination, with a boot or shoe, of a perforated elastic middle sole molded or otherwise formed with grooves or channels on both sides, so as to increase the elasticity of such middle sole and to produce two ventilating air-chambers, one above and one below such elastic middle sole; second, in providing the elastic middle sole with a depressed edge on either side to receive the edge of the upper and quarter when used in a rubber boot or shoe; third, in the combination of this peculiar elastic middle sole with the perforated inner sole; fourth, in providing the elastic intermediate lift of the heel with a metal plate embedded within the lift, which is molded around it, for holding the heads of the securing screws or nails and preventing them from working through by the movement of the heel; fifth, in the combination of the heel provided with the elastic lift, having the embedded metal plate, and having vertical holes passing through said elastic lift, with holes extending up into the interior of the boot or shoe at its heel, for ventilating the heel of the boot or shoe; sixth, in the combination of the perforated elastic middle sole, grooved on both sides to form two air-chambers, with an elastic heel having one or more air-chambers connected with the air-chambers of the sole; and, further, in the combination, construction, and arrangement of the principal parts composing my ventilating boot or shoe, all as more fully hereinafter explained.

In the accompanying drawings, forming a part hereof, Figure 1 is a vertical central lon-

itudinal section of the foot portion of a boot or shoe having my improved yielding and ventilating sole and heel; Fig. 2, a cross-section of the same near the toe, on line 22; Fig. 3, a cross-section through the heel, on line 33; Fig. 4, a cross-section of one edge of the sole of a rubber boot, showing the position of the upper between the outer sole and the elastic middle sole; Fig. 5, a bottom view of the perforated elastic middle sole; Fig. 6, a cross-section, on a larger scale, of a small portion of this elastic sole; Fig. 7, a separate view of the elastic heel-lift, with the position of the metal plate indicated by dotted lines, and Fig. 8 a separate view of the metal plate.

Like letters denote corresponding parts in all the figures.

A is the upper and quarter of a boot or shoe; B, the outer sole; and C, the inner sole, the latter being provided with perforations *a* at the toe and heel, and, if desired, throughout the body of the sole, which holes are of any suitable size, shape, and number, it only being necessary that the openings should be sufficient to allow the air to escape freely from the chambers of the sole and heel when they are compressed, so as not to burst the boot or shoe at any point.

Between the inner and outer soles is placed an elastic middle sole, D, made of india-rubber or other suitable elastic material. This middle sole has a number of perforations, *b*, and is molded or otherwise formed with intersecting grooves or channels *c* on each side, which, when the elastic sole is placed between the inner and outer soles, form two air-chambers, one above and one below the elastic sole. These air-chambers are kept expanded by the elastic projections *d*, formed by the intersecting grooves; but in walking the pressure brought to bear upon the inner sole causes such projections to give and the air-chambers to be contracted, expelling most of the air contained in them, and when the projections are relieved of this pressure (as when the foot is raised) they will expand the air-chambers and cause a partial vacuum therein, which will draw in fresh air. This elastic middle sole may be covered on top and bottom by thin sheets E of rubber cloth or other material; but these sheets can be dispensed with. If

used the upper sheet, E, would be perforated, while the lower sheet would be imperforate except at the heel.

In a leather boot or shoe the elastic middle sole would be smaller than the inner and outer soles, and be surrounded by welts F, placed between the inner and outer soles, as shown in Figs. 2 and 3; but in a rubber boot, Fig. 4, the middle sole would be nearly or quite the same size as the bottom of the boot, and would have its edge depressed, as shown at e in Figs. 4 and 5, either on its lower or upper side, to make room for the upper and quarter.

G is the heel of the boot or shoe, having an elastic intermediate lift, H. This lift is molded around a metal plate, I, provided with holes or notches f, which catch the heads of the fastening nails or screws, and prevent them from working through the lift. This elastic lift is first secured to the leather lift K by screws or nails g, which are driven into the elastic lift till their heads strike against the metal plate. Then the partially-formed heel is secured to the outer sole, or to one or more lifts of leather fastened thereto, by screws or nails h, which are driven through holes in the lift K and in the elastic lift till their heads are caught by the metal plate. The holes in the lift K may then be plugged up, as shown, or the outer wearing-lifts, L, may be secured thereto without filling up such holes.

It will be noticed that the metal plate I does not extend to the outer edge of the elastic lift, which enables such lift to be made solid at its edges.

The elastic lift H has one or more openings, i, made through it, which connect with the double air-chamber of the boot or shoe and directly with the interior of the boot or shoe at its heel. Sheets of rubber cloth may be placed above and below the elastic lift H, but can be dispensed with.

The shoe or boot may be provided with the removable supplementary insole m, which is grooved on its under side and is perforated; but the ventilating devices will operate without such supplementary insole, and I therefore do not wish to be limited to its use.

The air-chambers described of the boot or shoe may have either or both of the connections with the external air shown in the patent already granted to me and before referred to, or they may have any other suitable connections with the external air, or they can be used with-

out any such connections, and force and exhaust the air through the open top of the boot or shoe.

The peculiar elastic middle sole gives greater elasticity to the sole of the boot or shoe, and also produces a more complete ventilation than the elastic middle sole, which is grooved only on one side; and the embedded metal plate in the elastic lift of the heel securely holds the fastening nails or screws, the heads of which, but for such plate, would wear or work through the elastic lift, and the heel would become loose or be detached.

What I claim as my invention, and desire to secure by Letters Patent is—

1. In a boot or shoe, the perforated elastic middle sole, D, grooved or channeled on both sides, so as to form air-chambers above and beneath said middle sole, extending the entire width of the boot or shoe, substantially as and for the purpose set forth.

2. In a boot or shoe, the perforated and grooved elastic middle sole, D, having depressed edge e, substantially as and for the purpose set forth.

3. In a boot or shoe, the combination, with the perforated inner sole, of the perforated elastic middle sole, D, grooved or channeled on both sides and forming air-chambers both above and below said middle sole, extending the entire width of the boot or shoe, substantially as described and shown.

4. In a boot or shoe, the intermediate elastic heel-lift, H, having the metal plate I embedded therein, and the screws g h, for securing the elastic lift to the adjoining leather lifts, substantially as described and shown.

5. In a boot or shoe, the intermediate elastic heel-lift, H, having metal plate I and air-openings i, which are connected with the interior of the boot or shoe at its heel, substantially as described and shown.

6. In a boot or shoe, and in combination, the solid outer sole, the perforated inner sole, the perforated elastic middle sole grooved on both sides, the heel having intermediate elastic lift provided with air-openings, and the embedded metal plate, constructed and arranged substantially as described and shown.

WILLIAM H. HANNAFORD.
